UNITED STATES PATENT OFFICE.

CLYDE J. COLEMAN, OF NEW YORK, N. Y., ASSIGNOR, BY MESNE ASSIGNMENTS, TO HALL SWITCH & SIGNAL COMPANY, OF NEW YORK, N. Y., A CORPORATION OF MAINE.

TRAFFIC-CONTROLLING APPARATUS.

1,088,807.

Specification of Letters Patent.

Patented Mar. 3, 1914.

Application filed February 2, 1910. Serial No. 541,642.

To all whom it may concern:

Be it known that I, CLYDE J. COLEMAN, a citizen of the United States, and a resident of the city of New York, county and State of New York, have invented certain new and useful Improvements in Traffic-Controlling Apparatus, of which the following is a specification.

My invention relates to traffic controlling apparatus, and more particularly to certain novel arrangements of circuits and electro-responsive devices for utilizing the current flowing in a track for operating stop devices and for indicating the condition of traffic, by means located in a cab or car.

An important feature of my invention is the arrangement of circuits whereby the electro-responsive device controlling the stop device on the cab, is connected in shunt to a portion of a track circuit in advance of the first uninsulated axle of the engine or car, the track circuit being completed through the uninsulated axle and receiving its energy from a source in advance of the vehicle, so that the automatic stop device is rendered ineffective to stop the vehicle as long as there is signaling current flowing through the rails to the vehicle, the electro-responsive device being normally energized by and responsive to current due to the drop of potential in the part of the track circuit to which it is in shunt.

Another object of my invention is to provide automatic stop devices controlled as above described, by means of which the train will be suddenly brought to a stop if it enters a block containing a broken rail; and by means of which the vehicle will be gradually checked if it enters a block in the rear of a block containing a preceding vehicle, or a block at the entrance of which, for any reason, a caution signal is displayed.

Another object of my invention is to provide means whereby the electro-responsive device may be placed under the control of the engineer and rendered temporarily inoperative to apply the brakes, so that the vehicle may be moved over tracks not equipped with current, and may also be run under conditions where the service brakes would otherwise be applied.

Other objects of my invention, such as the method of applying insulation to a front axle or axles of the vehicle, will more fully appear from the following description taken in connection with the accompanying drawings forming a part of this specification, in which—

Figure 1 shows diagrammatically my invention in its simplest form as applied to an engine or car. Fig. 2 is a diagrammatic view of the invention in which is shown the application of both the emergency and safety brakes under the control of the automatic stop device. Fig. 3 is a cross-sectional plan view of an axle having its wheels insulated therefrom. Fig. 4 is a similar view of one of the insulated wheels of an axle equipped with a suitable current collecting device. Fig. 5 is a cross-sectional view of the wheel shown in Fig. 4, taken on the line X—X; and Fig. 6 shows a detail.

Referring to the drawings (Fig. 1), 1—1 represent the rails of a track divided by suitable means into blocks A, B, with a source 2 connected across the rails of each of the blocks. I have shown my invention in connection with a track divided by insulation into suitable blocks for the reason that all direct current block signaling systems are so constructed, and it is with such systems that I propose to utilize my invention to a large extent, but it is to be understood that the form of the invention shown in Fig. 1 is equally applicable to tracks having continuous rails, without any insulation whatsoever, and with the source of current placed across the track at suitable intervals, the distance between successive sources comprising a block.

3 is the frame of an engine or car having its front axle or truck 4, known as the pony truck, insulated as diagrammatically shown at 5; the track circuit including the source 2, being closed through the rails 1—1 and the next rear axle or axles 6. Upon the vehicle is carried a sensitive relay 7 which is connected across the rails through wire 8', brushes 9—9' and the front wheels 10—10'; the relay being thus connected, is in shunt to that portion of the track circuit in the rear of the wheels 10—10', which includes

the portion of the rails in the rear of said wheels, and the axle or axles 6, 6 which complete the track circuit. The relay 7 being connected in shunt to a part of the track circuit will be normally energized by a current proportional to the drop of potential in that part of the track circuit. The vehicle 3 is shown as equipped with the usual braking apparatus, including the reservoir R, 10 the control valve CV and the train pipe TP from which extends a pipe 11 to which I apply a stop device which is shown for convenience in the form of a reciprocating valve having a casing 14 and a plunger with 15 a reduced stem 13 which is connected at its upper end to the core of a solenoid 15, which is in turn provided with a dashpot 16. The plunger of the valve 14 is biased by gravity, or by a spring 17, to a position for exhausting 20 the train pipe, and applying the brakes, and it is held by the solenoid 15, when energized, in a position to prevent the escape of air from said pipe. The solenoid 15 is connected in a local circuit 18 including battery 19, the circuit being closed by armature 25 20 as long as relay 7 is energized due to the presence of current in the track circuit.

The apparatus is normally in the position shown, in block A, Fig. 1, but should the car 30 pass into a block already occupied as shown in block B, the current from the battery ahead will be shunted through the preceding vehicle, thus deenergizing the relay 7, permitting its armature to drop, and opening the 35 circuit 18, thus deenergizing the solenoid 15 and permitting the plunger to be moved by the spring 17 into a position to exhaust the train pipe and apply the brakes. The dashpot 16 connected to the core of solenoid 15 is 40 equipped with any well known form of check valve, such as that shown in Fig. 6, so as to provide a slow movement for the plunger of valve 14 at times when relay 7 is momentarily deenergized, such as when the car is passing 45 over insulating sections, so that the dashpot while retarding the drop of the valve plunger for a sufficient length of time to prevent the application of the brakes during the short period that relay 7 is thus deenergized, 50 will permit a quick movement of the plunger when solenoid 15 is energized.

It will be seen that by connecting relay 7 in shunt to a part of the track circuit in advance of the first uninsulated axle, so that 55 the relay is energized by current in proportion to the drop of potential in a portion of the track circuit in advance of said axle, I obtain an automatic stop system with which vehicles may be equipped without in any 60 way changing the signaling system already installed, and without requiring any alteration to the rolling stock except the insulating of the front truck or axle.

While I have shown relay 7 controlling

the application of "emergency brakes", I do 65 not wish to be understood as limiting my invention to this particular use, since it is obvious that the relay may be utilized for controlling the car in any manner, and while I have shown my invention in connection with 70 an "automatic" air-brake system, it is obvious to those skilled in the art that it may be utilized in connection with "straight air" systems.

In Fig. 2 I have shown my invention in a 75 form by means of which the application of either the "emergency" or "service" brakes may be automatically effected, dependent upon whether or not the vehicle has run past a danger or caution signal; and I have also 80 shown means in the cab for indicating the condition of traffic along the block. In this form of my invention I utilize a delicate three-position polarized relay 21, having a movable coil 22 connected to the brushes 85 9-9' so as to be in shunt to the portion of the track circuit in the rear of wheels 10, 10' as previously described in connection with Fig. 1, while a stationary coil 23 of the relay is energized from battery 24. The auto- 90 matic stop device in this case, for purpose of simplicity, is shown as consisting of two plunger valves 14, 14' having their stems connected to the cores of solenoids 15, 15', respectively, each of which is equipped with 95 dashpots 16-16', all precisely as described in connection with Fig. 1. The solenoid 15 is connected in a circuit including the battery 24, wire 25, wire 27, contacts 28 or 28', through the arm 29 carried by the movable 100 coil of the relay 22, and thence through contacts 30 or 30', according to the position of said arm, back to battery 24. Solenoid 15 is included in a circuit from battery 24 through wire 25, wire 26, wire 31, contact 32, arm 29, 105 and contact 30 back to the battery 24. Since relay 21 has its coil permanently energized, the movable coil 22 will be deflected to the left or right, according to the direction of the current flowing from battery 2 through 110 the track circuit, as determined by a current reverser 33; and will assume a neutral position when the coil 22 is deenergized due to failure of current in the track circuit.

With the circuits and apparatus as above 115 described, if the vehicle is on an unoccupied block, and with the block in advance also unoccupied, current from battery 2 will flow through the track circuit and through coil 22 of relay 21 in a direction to hold contact 120 arm 29 in the position shown, so as to energize, through previously traced circuits, solenoids 15 and 15' thus holding both valves of the stop device in a position to prevent the escape of fluid pressure from the train 125 pipe, and preventing the application of the brakes through the stop device. But if the vehicle enters a block protected by a caution

signal, the current in the track circuit of that block, due to the suitably operated current reverser 33, will be in a direction to throw contact arm 29 against contacts 28' and 30', thus opening the circuit of solenoid 15' but holding the circuit of solenoid 15 closed through said contacts. The deenergization of solenoid 15' will permit the movement of the plunger of valve 14' so as to apply the "service brakes," while the application of the "emergency brakes" through the stop device is prevented by the energization of solenoid 15.

In order to permit the vehicle to continue in the block under the caution signal, it is necessary for the engineer to move a switch 34, against the action of a spring 35, into engagement with suitable contacts 36 so as to energize the solenoid 15', through said contacts, and wires 37, 38, thus holding the valve 14' closed and permitting the vehicle to proceed; but if the engineer should, at any time, remove his hand from the switch 34, the "service brakes" would be immediately applied to stop the train. The necessity of the engineer keeping his hand on the switch to hold the valve closed, is a continual reminder to him of the fact that he is traveling under a caution signal. Should the vehicle enter a block already occupied by another vehicle, or enter a block containing a broken rail, the coil 22 will be deenergized, thus permitting arm 29 to assume a neutral position, deenergizing both solenoids 15-15', and applying the "emergency brakes" through valve 14. If the vehicle is in a yard, or upon any track not equipped with traffic-controlling current, it is necessary to provide means under the control of the engineer, by which he can render the stop device ineffective to apply the brakes, so that he may move the vehicle over such track, and for this purpose I provide a second bridging contact on the switch 34 which engages suitable contacts 39, connected to wires 38 and 40, for completing a circuit through solenoid 15. The switch 34 and the contacts 36 and 39 are so arranged that contacts 36 are closed when the switch is first moved, as will be the case when the vehicle is traveling under a caution signal, but contacts 39 will not be closed unless the switch is moved farther against the spring, so that should a rail become broken in front of the vehicle while thus traveling under a caution signal, and coil 22 become deenergized, the circuit to relay 15 will be opened through contacts 28'-30' and the emergency brakes will be applied, which would otherwise not be done if the switch 34 was at that time bridging contacts 39. When the engineer desires to move his vehicle out of a yard not equipped with traffic-controlling currents, or over any tracks not so equipped, it is necessary for

him to exert greater force in moving the switch 34 into engagement with contacts 39; in which position of the switch both of the solenoids 15-15' will be energized, holding the valves 14-14' closed and permitting him to move his vehicle. In connection with this form of my invention I have shown a miniature three-position signal 41 mounted on the vehicle to indicate to the engineer the condition of traffic along the block. The signal is shown diagrammatically as operated by two windings 42, 43 acting on the same core, the windings and the core being so arranged that when the winding 43 only is energized, the signal will assume a caution position, while if the winding 42 is also energized, the signal will assume a safety position. The winding 42 is connected in the following circuit: from battery 24, wire 44, through said winding, wire 45, wire 31, thence through contacts 32, arm 29, and contact 30 back to the battery; while winding 43 is connected in a circuit from the battery through wire 44 and said winding, wire 46, wire 27, thence through contacts 28 or 28', arm 29 and contacts 30 or 30', back to the battery. It will thus be seen that when the arm 29 is in the position shown, which is the position it assumes when traveling under a clear signal, the circuit to both coils 42 and 43 will be closed, and the semaphore 41 will indicate "clear"; while if the arm 29 is in the position it assumes when the train runs past a caution signal, coil 43 only will be energized, thus holding signal 41 at caution; and when arm 29 is in its neutral position, as in the case when the track circuit fails, neither of the coils will be energized, thus permitting the signal 41 to go to danger.

By including in the track circuit a source in advance of the vehicle, the track rails which are of opposite polarity, and an uninsulated axle of the vehicle, and by connecting the relay in shunt to a portion of the track circuit so as to be normally energized by the presence of current in the track circuit, and responsive to current due to drop of potential in the portion of the circuit to which it is in shunt, a perfect indication of the condition of the block ahead is obtained. The control of the vehicle is absolutely reliable, since the presence of a train in a block ahead, or in the block in which a vehicle is advancing, will cause a reversal of current or a failure of current of the track circuit, as the case may be, thus applying the service or emergency brakes regardless of whether or not the vehicle has passed a clear signal at the entrance of that block. The system therefore gives absolute assurance regardless of whether the danger condition of the block arose after or before the vehicle entered it.

Since the relay 7 must be responsive to current proportional to the drop of potential

in the short portion of the track circuit to which it is connected in shunt, obviously the coil of the relay receiving its energy from the track circuit must be of a very low resistance and the relay must be designed to operate in response to the very slight amount of current which normally flows through the coil of the relay due to its shunt connection to a portion of the track circuit 19 in advance of the first uninsulated axle. In order to facilitate the flow of current through the coil of the relay receiving its energy from the track circuit, I use copper or aluminum brushes making contact with suitable collector rings on the insulated axle which are also made of highly conductive metal, and I mount the relay in the front of the vehicle and on some suitable support near the point from which the relay receives 20 its energy from the track circuit and I use a comparatively heavy conductor running from the collector or brush to the relay coil in order to cut down as much as possible the resistance of the circuit through the coil 25 so as to facilitate the flow of current through this path.

While I have shown and described my invention as used with direct current for the reason, as previously stated, that steam roads 30 are now equipped with such current, it is obvious that it may be equally applicable to roads equipped with alternating current, and in fact by the use of alternating current, the relay in shunt to a portion of the track 35 circuit need not be made as delicate as when used with direct current in the track circuit, since, due to the impedance of the rails, a greater drop of potential is obtainable in the portion of the track circuit to which it is in 40 shunt than is the case when direct current is used.

While I have shown and described the switch 34 under the control of the driver of the vehicle for the purpose of rendering the 45 relay ineffective to apply the brakes to the stop device, it is obvious to those skilled in the art that many other arrangements for accomplishing this purpose may be used, and I wish to be understood as including all such 50 modifications in the scope of my invention.

Fig. 3 is a cross-sectional plan view of the insulated axle of the vehicle or of one of the axles of a pony truck, according as to whether or not the vehicle is equipped with 55 a single front axle or a pony truck having a plurality of axles. Insulating the wheels of an axle has been objected to due to the fact that the insertion of insulation anywhere in the axle tends to weaken it, unless the portion of the axle at which the insulation is placed is greatly increased in size to compensate for the weakening of the axle by the presence of the insulation. In order to insulate the wheels from each other without 60 weakening the axle and to be able to use the

present form of truck, I propose to apply the insulation in the following manner. The axle 47 to be insulated is shown as journaled in the frame 48 of the pony truck, only part of which is shown, the axle and truck being 70 of any standard form. 49 represents a collar preferably of fiber or compressed paper which is forced on the outer end of the axle, fitting snugly up against the shoulder 50 turned up on the axle, and 51 is a thin sleeve 75 of suitable insulating material such as fiber or compressed paper which is by means of hydraulic pressure forced on to the tapering part of the axle 52, and after this sleeve has been forced on in place, the wheel 53, preferably having a long hub, is forced on over it so as to fit tightly against the insulating collar 50. After the wheel has been forced in place a second insulating collar 54 is slipped on in front of the hub and held in place 80 either by suitably expanding the outer end of the axle or by a threaded nut 55 as shown. By insulating the wheels in this manner the strength of the axle is in no way affected and if the insulating sleeve and collars are 85 properly constructed their presence will add to the life of the truck since they will provide a very slight cushioning effect between the wheels and the axle, thus slightly reducing the vibrations transmitted to the latter. 90 Inasmuch as the track voltage is very low, usually varying from a half of a volt to five volts, the insulating parts need only be very thin, thus requiring but slight, if any, different size of the hub and axle. The insulating sleeve 51, after the hub is pressed over it, is completely protected from causes 95 of deterioration and the washers 50, 54, which need only be thick enough to give them sufficient mechanical strength to be 100 placed in position, will only be exposed on their edges, so that after the wheel has been forced on the axle and properly secured, there will be no danger of the insulation deteriorating to an extent sufficient to prevent the effectual insulation of the wheels 105 from the axle for the low voltage in connection with which they are used.

In Fig. 4 I have shown a cross-sectional plan view of one of the insulated wheels in which the insulating collar 49 and sleeve 51 are formed in one piece, and in which the wheel is held in place by expanding the end of the axle as is the usual practice for securing the wheels on their axles. In this view 115 I have also shown a metallic ring or strap 56, preferably formed of brass, copper or aluminum, at a suitable place on the hub of the wheel, to be engaged by a brush 57 to which one of the leads from the electro-responsive device is connected; it being understood that each of the insulated wheels is equipped with the same apparatus. In order to protect the ring and brush from 120 dust and dirt so that as good a contact as 125

130

possible will be assured, I provide a casing or housing 58, preferably formed of compressed paper or sheet metal, and secured to any suitable part of the frame of the vehicle, 5 or to the frame 48 of the pony truck as shown. In order to be able to place the housing around the collector ring after the wheel has been forced on the axle, and to facilitate the removal of the housing for the 10 purpose of inspecting the brushes and collector ring without disturbing their adjustment, I form the casing in two parts 59 and 60, one of which is secured to a suitable part of the frame as shown, the other part being bolted to the first part by bolts 61 or other suitable means as shown in Fig. 5.

While I have shown and described my invention in what I now consider its preferred forms, I do not wish to be understood as 20 limiting myself to the specific arrangements of circuits or apparatus herein shown and described, as it is obvious to those skilled in the art that various arrangements and changes may be made in the circuits for connecting the relay in shunt to a portion of a track circuit in advance of the first uninsulated axle of the vehicle so that it will be responsive to current due to the drop of potential in said portion of the track circuit, 25 and I do not wish to be understood as limiting myself to any of the arrangements shown and described other than as indicated in the appended claims.

What I claim as new and desire to secure 35 by Letters Patent of the United States is:—

1. The combination with a railroad track supplied at intervals with current giving the rails opposite polarity, of a traffic controlling electro-responsive device carried by a 40 car or train, and connections therefrom placing the same in shunt to a portion of the track circuit said track circuits being formed by the train and the track rails and the source ahead of the train, said electro-responsive device being constructed to be 45 operatively energized by current due to the normal drop of potential in said track circuit portion.

2. In combination with a railroad track 50 supplied at intervals with current giving the two rails opposite polarity, of a car or engine having an axle completing the track circuit and having a traffic controlling electro-responsive device receiving its energy 55 in shunt to a length of the track circuit in advance of the first axle completing said circuit and arranged to be operatively energized by the current caused by the normal drop of potential in said length of track.

3. In a traffic controlling system, the combination of the rails of a track, a source of current across the rails, a vehicle having an 60 axle bridging the rails and forming a part of the track circuit, and an electro-responsive traffic controlling device carried by the 65

vehicle and connected in shunt to a part of the track circuit to receive its energy from across the rails, and responsive to current due to the drop of potential in the part of the track circuit to which it is in shunt. 70

4. In a traffic controlling system, the combination of the rails of a track, a source of current across the rails, a vehicle having an axle bridging the rails and forming a part of the track circuit, a stop device carried by 75 the vehicle, and an electro-responsive device also carried by the vehicle for controlling said stop device and connected in shunt to a part of the track circuit to receive its energy from across the rails at a point in advance of said axle and controlled by current due to the drop of potential in the part of the track circuit to which it is in shunt. 80

5. In a traffic controlling system, the combination of the rails of a track, a source of current across the rails, a vehicle having an axle bridging the rails and forming a part of the track circuit, a second axle bridging the rails but having its wheels insulated one from the other, a stop device carried by the 85 vehicle, and an electro-responsive device for controlling said stop device connected through the wheels of the insulated axle across the track circuit in shunt to a portion thereof including the first axle, and controlled by current due to the drop of potential in said portion of the track circuit. 90

6. In a traffic controlling system, the combination of the rails of a track, a source of current connected across the rails, a current 100 reverser in the track circuit, a vehicle having an axle bridging the rails and forming a part of the track circuit, and an electro-responsive traffic controlling device carried by the vehicle and connected across the rails in shunt to a portion of the track circuit and responsive to current due to the drop of potential in the portion of the track circuit to which it is in shunt, said traffic controlling device having three functional positions, one of 105 which it assumes in response to current in the track circuit in a given direction, another of which it assumes in response to current in the opposite direction, and a third position which it assumes upon failure of 110 current in the track circuit. 115

7. In a traffic controlling system, the combination of the rails of a track, a source of current connected across the rails, a current 120 reverser in the track circuit for reversing the direction of current therein, a vehicle having an axle bridging the rails and forming a part of the track circuit, braking apparatus on the vehicle, a stop device carried by the vehicle and operatively related to the braking apparatus for effecting the application of the "emergency" or the "service brakes", and means including an electro-responsive device energized from the track circuit for controlling the automatic stop device to ef. 125 130

fect the application of the "emergency brakes" upon failure of current in the track circuit and to effect the application of the "service brakes" only, upon a reversal of current in said circuit.

8. In a traffic controlling system, the combination of the rails of a track, a source of current connected across the rails, a current reverser in the track circuit, a vehicle having an axle bridging the rails and forming a part of the track circuit, braking apparatus on the vehicle, a stop device carried by the vehicle and operatively related to the braking apparatus for effecting the application of the "emergency" or the "service brakes", electro-magnetic means for operating the stop device, and an electro-responsive device carried by the vehicle and energized by the track circuit and having at least three functional positions for controlling said electro-magnetic means, one of which it assumes when energized by current from the track circuit in one direction for controlling the electro-magnetic means to prevent the application of the brakes by the stop device, another of which it assumes upon reversal of the current in the track circuit, in which position it controls said electro-magnetic means for effecting the application of the "service brakes", and a third position which it assumes upon failure of the track circuit for controlling said electro-magnetic means for effecting the application of the "emergency brakes".

9. In a traffic controlling system, the combination of the rails of a track, a source of current connected across the rails, a current reverser in the track circuit, a vehicle having an axle bridging the rails and forming a part of the track circuit, braking apparatus on the vehicle, a stop device carried by the vehicle and operatively related to the braking apparatus for effecting the application of the "emergency" or the "service brakes", electro-magnetic means for operating the stop device, and an electro-responsive device carried by the vehicle and connected in shunt to a part of the track circuit to receive its energy from across the rails and controlled by current due to the drop of potential in the part of the track circuit to which it is in shunt, said electro-responsive device having at least three functional positions, in one of which it controls said electro-magnetic means for effecting through the stop device the application of the "emergency brakes", in another of which it controls said electro-magnetic means for effecting through the stop device the application of the "service brakes", and in its third position controlling said electro-magnetic means for rendering the stop device ineffective to apply the brakes.

10. In a traffic controlling system, the combination of the rails of a track, a source

of current connected across the rails, a current reverser in the track circuit, a vehicle having an axle bridging the rails and forming a part of the track circuit, braking apparatus on the vehicle, a stop device carried by the vehicle and operatively related to the braking apparatus for effecting the application of the "emergency" or the "service brakes", electro-magnetic means for operating the stop device, and an electro-responsive device carried by the vehicle and connected in shunt to a part of the track circuit to receive its energy from across the rails at a point in advance of said axle and controlled by current due to the drop of potential in the part of the track circuit to which it is in shunt, said electro-responsive device having at least three functional positions, in one of which it controls said electro-magnetic means for effecting through the stop device the application of the "emergency brakes", in another of which it controls said electro-magnetic means for effecting through the stop device the application of the "service brakes", and in its third position controlling said electro-magnetic means for rendering the stop device ineffective to apply the brakes.

11. In a traffic controlling system, the combination of the rails and a track, a source of current connected across the rails, a current reverser in the track circuit, a vehicle movable upon said rails, braking apparatus on the vehicle, a stop device carried by the vehicle and operatively related to the braking apparatus for effecting the application of the brakes, controlling means for the stop device receiving its energy from the track circuit and responsive both to current of a given direction in the track circuit and to failure of current in the track circuit for effecting the application of said brakes through the stop device, and means under the control of the driver of said vehicle for rendering said stop device ineffective to apply the brakes in response to current in the track circuit but permitting the application of the brakes by the stop device upon failure of current in the track circuit.

12. In a traffic controlling system, the combination of the rails of a track, a source of current connected across the rails, a current reverser in the track circuit, a vehicle movable upon the rails, braking apparatus on the vehicle, a stop device carried by the vehicle and operatively related to the braking apparatus for effecting the application of the brakes, electro-magnetic means for operating the stop device, an electro-responsive device carried by the vehicle and responsive both to current of a given direction in the track circuit and to failure of current in said circuit for effecting the application of the brakes through said electro-magnetic means and stop device, and

means under the control of the driver of the vehicle for preventing the application of the brakes by the stop device in response to current in the track circuit but permitting 5 the application of the brakes by the stop device upon failure of current in the track circuit.

In testimony whereof, I have signed my name to this specification, in the presence of two subscribing witnesses.

Corrections in Letters Patent No. 1,088,807.

It is hereby certified that in Letters Patent No. 1,088,807, granted March 3, 1914, upon the application of Clyde J. Coleman, of New York, N. Y., for an improvement in "Traffic Controlling Apparatus," errors appear in the printed specification requiring correction as follows: Page 1, line 98, after the word "wire" insert the reference-numeral 8; same page, line 100, strike out the word "is"; and page 2, line 103, for the reference-numeral "15" read 15'; and that the said Letters Patent should be read with these corrections therein that the same may conform to the record of the case in the Patent Office.

Signed and sealed this 21st day of July, A. D., 1914.

[SEAL.]

R. F. WHITEHEAD,
Acting Commissioner of Patents.

Corrections in Letters Patent No. 1,088,807.

It is hereby certified that in Letters Patent No. 1,088,807, granted March 3, 1914, upon the application of Clyde J. Coleman, of New York, N. Y., for an improvement in "Traffic Controlling Apparatus," errors appear in the printed specification requiring correction as follows: Page 1, line 98, after the word "wire" insert the reference-numeral 8; same page, line 100, strike out the word "is"; and page 2, line 103, for the reference-numeral "15" read 15'; and that the said Letters Patent should be read with these corrections therein that the same may conform to the record of the case in the Patent Office.

Signed and sealed this 21st day of July, A. D., 1914.

[SEAL.]

R. F. WHITEHEAD,

Acting Commissioner of Patents.
